Primary Examiner — Selina Sikder(74) *Attorney, Agent, or Firm* — Crestron Electronics, Inc.(57) **CLAIM**

The ornamental design for a wall mounted button panel, as shown and described.

DESCRIPTION

FIG. 1 shows a front perspective view of a wall mounted button panel according to an embodiment.

FIG. 2 shows a front elevation view of the wall mounted button panel.

FIG. 3 shows a left side view of the wall mounted button panel.

FIG. 4 shows a right side view of the wall mounted button panel.

FIG. 5 shows a top view of the wall mounted button panel; and,

FIG. 6 shows a bottom view of the wall mounted button panel.

The broken lines in the figures depict portions of the wall mounted button panel that form no part of the claimed design.
